Primary Examiner — Cynthia Ramirez*(74) Attorney, Agent, or Firm* — Law Office of Mark Brown LLC; Mark E. Brown; Christopher M. DeBacker(57) **CLAIM**

The ornamental design for a bag receiving basket, as shown and described.

DESCRIPTION

FIG. 1 is a perspective view of a bag receiving basket;
 FIG. 2 is a perspective view of thereof, demonstrating the bag receiving basket with the typical environment of a plastic shopping bag shown by broken lines;
 FIG. 3 is a front side elevational view of the bag receiving basket, the rear side is a mirror image thereof;
 FIG. 4 is a left side elevational view thereof, the right side is a mirror image thereof;
 FIG. 5 is a bottom plan view thereof; and,
 FIG. 6 is a top plan view thereof.
 The broken line showing of a bag in FIG. 2 is included for the purpose of illustrating environment and forms no part of the claimed design.
